UNITED STATES PATENT OFFICE.

FREDRICK B. ADAM, OF ST. LOUIS, MISSOURI, ASSIGNOR TO FRANK ADAM ELECTRIC COMPANY, OF ST. LOUIS, MISSOURI, A CORPORATION OF MISSOURI.

FASTENING DEVICE FOR PANEL-BOARD CABINETS.

1,027,397.

Specification of Letters Patent. Patented May 28, 1912.

Application filed July 19, 1911. Serial No. 639,401.

To all whom it may concern:

Be it known that I, FREDRICK B. ADAM, a citizen of the United States, residing at St. Louis, Missouri, have invented a certain new and useful Improvement in Fastening Devices for Panel-Board Cabinets, of which the following is a full, clear, and exact description, such as will enable others skilled in the art to which it appertains to make and use the same.

This invention relates to panel board cabinets, and particularly to the means used in such structures for securing the front of the cabinet to the box which forms the body portion of the cabinet.

Panel board cabinets usually consist of a sheet metal box that is set into a wall so as to form a housing for the panel board and a removable front that is arranged in position after all of the wires have been connected to the panel board. This removable front generally consists of a door and a frame or "trim" that surrounds the door and which is wide enough to cover the joint or space between the box and the edges of the opening in the wall in which the box is arranged, said frame being connected to the box by means of screws or bolts which pass through the frame and through a flange on the front edge of the box. If the box is not set exactly plumb in the wall the frame or trim which forms the front of the cabinet will also be crooked because said frame is held in position by means of fastening devices which pass through same and through openings in the flange on the front edge of the box. Furthermore, if the box springs slightly or warps out of shape a great deal of time is wasted during the operation of securing the front frame in position; especially if the front frame is formed of metal as is very often the case with the panel board cabinets now in general use.

One object of my invention is to provide a panel board cabinet of novel construction which is so designed that the frame which forms part of the front of the cabinet can be set plumb even if the box which forms the body of the cabinet is set crooked or not exactly plumb.

And another object is to provide a clamp of novel construction that is adapted to be arranged on the inside of a member to which an object is to be clamped and which is so

designed that it will not shift into an inoperative position when it is being tightened.

Figure 1 of the drawings is a horizontal sectional view of a portion of a panel board cabinet constructed in accordance with my invention; Fig. 2 is a vertical sectional view taken on the line 2—2 of Fig. 1 looking in the direction indicated by the arrow; and Fig. 3 is a perspective view of one of the clamps which forms part of the means for retaining the front frame in position.

Referring to the drawings which illustrate the preferred form of my invention, A designates a box that is set into a wall so as to form a housing for a panel board B. Said box is preferably formed of sheet metal and is provided at its front edge with an inwardly projecting portion or flange 1 which extends parallel to the rear wall of the box, as shown in Fig. 1, the box either having a continuous flange or a number of short flanges. The front of the cabinet is detachably connected to the box A, and consists of a door C and a frame D which surrounds said door, said frame being wide enough to cover the joint or space between the box and the edges of the opening in the wall in which the box is arranged, as shown clearly in Fig. 1. The frame D is secured to the box A by means of clamps E and threaded fastening devices such, for example, as bolts F, which pass through said frame and through the clamps E so as to draw said clamps into intimate engagement with the flange 1 on the box A, as shown in Fig. 1. Each of the clamps E consists of a strip of metal that is bent or doubled, as shown in Fig. 3, so as to produce two parallel portions 2 through which the bolt F passes, said parallel portions 2 being provided with threaded openings 3 for receiving said bolt.

In order to insure sufficient friction between the bolt F and the clamp E to cause the long arm of said clamp to move into engagement with the side wall of the box A when the bolt is introduced into the threaded opening 3 in the clamp, I bend the portions 2 of the clamp toward each other after the screw-threaded openings 3 have been formed therein so as to distort the threads slightly with relation to the threads on the bolt and thus cause them to grip the threads of the bolt F tightly when said bolt is in-

serted in the clamp. In other words, I provide the clamp E with two approximately parallel portions 2 having screw-threads which are distorted slightly with reference to the threads on the bolt F so as to cause the clamp to turn with the bolt until the long arm of the clamp strikes against the side wall of the box A, as shown in Fig. 2. Thereafter the clamp will remain at rest while the bolt F is being tightened or screwed farther into the clamp and consequently said bolt will force the front frame D tightly against the flange 1 on the box and also draw the long arm of the clamp 15 tightly against the inner face of said flange 1.

While I have herein illustrated only one of the clamping devices that is used at the side of the box, it will, of course, be understood that similar clamping devices are used at the top and bottom of the box and at both sides of the box, the box being provided at its front edge with an inwardly projecting flange 1 that extends around the 25 entire edge of the box.

A panel board cabinet of the construction above-described can be installed quickly and easily because the workman does not have to waste time in springing the box 30 back into shape in case it is warped so as

to bring the openings in the flange 1 and in the frame D into alinement with each other, as was necessary with the panel board cabinets heretofore in general use; and another desirable feature of such a cabinet is that 35 the front frame D can be set perfectly plumb even if the box A is set crooked because said box is not provided with any threaded openings which have to aline with openings in the front frame D. 40

Having thus described my invention, what I claim as new and desire to secure by Letters Patent is:

A fastening device comprising spaced parallel portions, one of which is adapted to engage a stationary member, and a screw or bolt passing through the exposed face of the object with which the device is used and projecting into the screw-threaded openings in the parallel portions of the device, the 45 screw-threads on said parallel portions being distorted with relation to the screw-threads on said screw.

In testimony whereof I hereunto affix my signature in the presence of two witnesses, 50 this seventeenth day of July 1911.

FREDRICK B. ADAM.
